SHIRT INSERT BOARD

Robert Peiffer, Myerstown, Pa., assignor to S. Liebovitz & Sons, Inc., New York, N. Y., a corporation of New York

Application August 22, 1935, Serial No. 37,286

3 Claims. (Cl. 223—71)

This invention relates to shirt insert boards and more particularly boards of the type used by shirt manufacturers and others, and on which shirts or like garments are wrapped or folded.

5 An object of the invention is to provide a board of this character having a form for supporting the collar of the shirt or garment in erect position.

10 A further object is to provide a board having a foldable tab which may be readily folded to form a collar support.

Another object of the present invention is to provide means for holding and securing the tab in its folded position.

15 Still further objects of the invention are to provide boards of the character described, which are inexpensive to manufacture and simple to manipulate.

The boards of my invention are adapted to be stored with foldable tabs in flat condition so as to occupy a minimum amount of space in storage.

The accompanying drawing illustrates a preferred embodiment of the invention in which:

20 Figure 1 represents a top plan view of the board with the foldable tab in flat condition;

Fig. 2 is a similar view showing the tab in its folded or collar supporting position.

25 Fig. 3 is a sectional view taken on the line 3—3 of Fig. 2; and,

Fig. 4 is a perspective view of the board with a shirt wrapped thereon, and the collar of the shirt supported in erect position.

The board 10 is substantially rectangular in form and is made of cardboard or other suitable, inexpensive, relatively stiff material.

A foldable tab 11 preferably having inclined side edges 12—12, extends outwardly from the middle portion of the upper edge of the board.

40 The free end of the tab is provided with a tongue 13 having shoulders 14—14 at its base. The tongue is preferably formed with a tapered end as shown.

45 A pair of parallel slits 15—15 extend inwardly from the upper end of the board at the base of the tab 11. The tab has three transversely extending score lines, 16—17 and 18 along which it may be bent or folded, which score lines divide the tab into three sections, namely: a base or lower section 19, an intermediate section 20, and an upper section 21.

50 A slot or opening 22 is cut through the board at the base of the tab 11, intermediate the slits 15—15, for receiving the tab section 21 when the tab is folded as hereinafter described. A slit 23

is formed through the board, below the slot 22, for receiving and frictionally engaging the tongue 13. An opening 24, of less width than the slit 23, may be formed directly above the slit so that the tongue may be easily slipped through the slit. 5 When the tongue is inserted in the slit, the shoulders 14—14 act as stops. This construction provides means for interlocking the free end of the tab in the openings, and a simple means for effectively holding and securing the folded collar supporting tab in its folded position.

The lower edge of the board may have the usual notch 25 cut therein for conveniently centering the centre pleat 26 of the shirt 27 on the board.

In using the board, the section 19 of the tab is 15 bent up on the score line 16; and section 20 is bent down on the score line 17; and, the section 21 is bent forward on the score line 18 and is inserted through the slot 22 so as to lie partly on the upper surface of the board. The tongue 14 is passed downwardly through the slit 23 and lies against the under-surface of the board. The tab when thus folded and secured, forms an upright triangular collar support, as best seen in Fig. 3. The shirt 27, is wrapped or folded around the board, with its collar 28 positioned on the support provided by the folded tab, the support being inserted in the rear of the collar between the collar band and the collar top.

20 It is to be understood that various modifications in the details of construction and arrangement of parts hereinabove described may be made within the scope of the invention.

30 What I claim is:

1. A shirt insert board comprising a substantially rectangular flat board of relatively stiff material having a tab extending outwardly from one edge, a pair of slits extending inwardly from said edge to define the base of the tab, transverse score lines dividing the tab into three foldable sections and on which the tab may be folded to form a collar support, a transverse slot in the base of the tab through which the outermost section of the tab may be passed when the tab is in folded position, and a slit in the board below said slot for interlocking engagement with the free end of the tab to hold the tab in folded position.

35 2. A shirt insert board comprising a substantially rectangular flat board of relatively stiff material having a tab extending outwardly from one edge, a locking tongue at the free end of the tab, a pair of slits extending inwardly from said edge to define the base of the tab, transverse score lines dividing the tab into three foldable sections and on which the tab may be folded to form a 50 55

collar support, a transverse slot in the base of the tab through which the outermost section of the tab may be passed when the tab is in folded position, and a slit in the board below said slot for interlocking engagement with the tongue of the tab to hold the tab in folded position.

3. A shirt insert board comprising a flat board having a tab along one edge, said tab being folded on three parallel score lines to form an upright

collar support and having a locking tongue at its free end, a slot in the base of the tab through which the free end of the tab is inserted in folded position, and a slit below the slot through which the tongue is passed downwardly against the lower surface of the board to lock the tab in folded position.

ROBERT PEIFFER.
